RAILWAY BRAKING APPARATUS

Herbert L. Bone, Pittsburgh, Pa., assignor to The
Union Switch & Signal Company, Swissvale,
Pa., a corporation of Pennsylvania

Application June 5, 1935, Serial No. 25,118

23 Claims. (Cl. 303—20)

My invention relates to railway braking apparatus, and has for an object the provision of improved means for automatically controlling the braking action of a car retarder in accordance with the speed of a car passing therethrough.

I will describe two forms of apparatus embodying my invention, and will then point out the novel features thereof in claims.

10 In the accompanying drawings, Fig. 1 is a view, partly sectioned and partly diagrammatic, illustrating one form of apparatus embodying my invention. Fig. 2 is a view similar to Fig. 1 illustrating another form of apparatus embodying my invention.

15 Similar reference characters refer to similar parts in both views.

Referring first to Fig. 1, the reference characters 1 and 1^a designate the track rails of a stretch of railway track over which cars normally move in the direction indicated by the arrow under such conditions that it is desirable to at times control the speed of the cars automatically. For example, the stretch of track here shown might be in a classification yard of the "hump type" through which cars move under the influence of gravity. It is obvious that in service of this kind, the speed of individual cars or strings of cars will vary through wide limits, depending among other things, upon the speed at which they go over the hump, the temperature, the weight of the car and its contents, and the condition of the car as to whether it is a free running car or otherwise.

30 In order to control the speed of the cars, the stretch of track illustrated in the drawings is provided with a car retarder R which, in the form here shown, comprises two braking bars 2 and 3 extending parallel with, and located on opposite sides of, rail 1, and two similar braking bars 2^a and 3^a extending parallel with, and located on opposite sides of, rail 1^a.

35 The braking bars 2, 3, 2^a and 3^a are operated by a fluid pressure motor M comprising a cylinder 4 containing a reciprocable piston 5 attached to one end of a piston rod 6. The braking bars 2, 3, 2^a and 3^a are operatively connected with the piston rod 6 through a suitable linkwork including a bell crank 7 and a lever 8 pivotally supported at point 9. When piston 5 occupies its extreme right-hand position, in which it is illustrated in the drawings, the braking bars occupy their non-braking or ineffective positions in which they are out of engagement with

the wheels of a car traversing the rails 1 and 1^a. When piston 5 is moved to its left-hand position, however, as when fluid pressure is admitted to the right-hand end of cylinder 4, the braking bars 2, 3, 2^a and 3^a are moved toward the associated rail to their effective or braking positions in which they will engage the wheels of a car traversing the rails 1 and 1^a, to retard the speed of the car.

10 The braking bars 2, 3, 2^a and 3^a are constantly biased to their non-braking positions by any suitable means here shown as a spring 20 which is interposed in the cylinder 4 between the left-hand end of the cylinder and the piston 5.

15 The motor M is controlled by two magnet valves V¹ and V², each comprising a valve stem 10 biased to an upper position by means of a spring 11, and provided with a winding 12 and an armature 13. When valve V¹ is energized as shown in the drawings, valve stem 10 of this valve is moved downwardly against the bias of spring 11, and a pipe 14 which communicates with the right-hand end of cylinder 4 of motor M is then connected with atmosphere through a port 15. When valve V¹ is deenergized, however, pipe 14 is disconnected from atmosphere and is connected with a pipe 16 leading to valve V². When valve V² is energized, valve stem 10 of this valve moves downwardly, and connects pipe 16 with a pipe 17 which is constantly supplied with fluid pressure, usually air, from a suitable source not shown in the drawings, but when valve V² is deenergized, as shown in the drawings, pipe 16 is then disconnected from pipe 17. It will be apparent, therefore, that 20 when valve V¹ is energized, the region of the cylinder 4 of motor M between the piston 5 and the right-hand end of the cylinder is connected with atmosphere, so that the braking bars of the car retarder will then be held in their ineffective or non-braking positions by the spring 20. When, however, valve V¹ is deenergized and valve 25 V² is energized, fluid pressure will be supplied to the right-hand end of cylinder 4 of motor M, thus causing the braking bars to move to their effective or braking positions. It will be obvious that when the braking bars are moved to their braking positions, they will exert a braking force which is proportioned to the pressure of the fluid which is then supplied to the right-hand end of 30 motor M.

35 The valves V are controlled in part by a plurality of pressure responsive devices P²⁰⁻³⁰, P⁴⁵⁻⁵⁵ and P⁷⁰⁻⁸⁰, each comprising a Bourdon tube 21 connected to a pipe 14^a which communicates with 40

the pipe 14, so that these Bourdon tubes are constantly subjected to the pressure of the fluid in the right-hand end of cylinder 4 of motor M. Each Bourdon tube controls two contacts 22-22^a and 22-22^b. The pressure responsive devices P²⁰⁻³⁰, P⁴⁵⁻⁵⁵ and P⁷⁰⁻⁸⁰ are so constructed and so adjusted that they will operate successively as the pressure in the region of cylinder 4 between the piston 5 and the right-hand end of the cylinder increases. For example, for all pressures below 20 pounds per square inch, the contacts 22-22^a of each of these devices is closed. If the pressure exceeds 20 pounds per square inch, however, contact 22-22^a of device P²⁰⁻³⁰ opens, and if the pressure exceeds 30 pounds per square inch, contact 22-22^b of device P²⁰⁻³⁰ closes. In similar manner, the pressure responsive devices P⁴⁵⁻⁵⁵ and P⁷⁰⁻⁸⁰ are adjusted to open their contacts 22-22^a at 45 and 70 pounds per square inch, respectively, and to close their contacts 22-22^b at 55 and 80 pounds per square inch, respectively. Of course, these specific pressures are not essential but are only mentioned for purposes of explanation.

25 The valves V are also controlled in part by means of two slow releasing relays A and B which relays, in turn, are controlled by speed responsive apparatus in a manner which will be described in detail hereinafter.

30 The valves V are further controlled by means of a manually operable lever L which, as here shown, is capable of assuming five positions, indicated by dotted lines in the drawings, and designated by the reference characters p¹ to p⁵, inclusive. Operatively connected with the lever L is a contact arm 23 which selectively engages a plurality of fixed contacts 23¹, 23², 23³, 23⁴ and 23⁵ to close a contact 23-23¹, 23-23², 23-23³, 23-23⁴ or 23-23⁵, according as lever L occupies 40 its p¹, its p², its p³, its p⁴ or its p⁵ position.

45 The lever L will usually be located at a point remote from the braking apparatus, as in the control cabin of a classification yard car retarder system, and will be connected with the braking apparatus by means of line wires extending from the control cabin to the braking apparatus.

50 As shown in the drawings, the relays A and B are both deenergized and the lever L occupies its p¹ or off position. Under these conditions all circuits for valve V² are interrupted, and a circuit for valve V¹ is closed, which latter circuit passes from a suitable source of current here shown as a battery C through wire 24, back contact 25-25^a of relay A, wire 26, contact 23-23¹ of lever L, line wire 27, wires 28, 29, 30 and 31, winding 12 of valve V¹, and wire 32 back to battery C. Valve V² is therefore deenergized and valve V¹ is energized. Since valve V² is deenergized, pipe 17 is disconnected from pipe 16 and the supply of fluid pressure to cylinder 4 is therefore cut off, and since valve V¹ is energized, cylinder 4 is connected with atmosphere. The braking bars are therefore held in their ineffective or non-braking positions by the spring 20. 60 The contact 22-22^a of each of the pressure responsive devices P is closed, and the contact 22-22^b of each of these devices is open.

65 I will now assume that with the relays A and B both deenergized the operator moves lever L to its p² position. Under these conditions, the circuit which was previously closed for valve V¹ will become interrupted at contact 23-23¹ of lever L and a circuit for valve V² will become closed at contact 23-23² of lever L, which latter 75 circuit may be traced from battery C through

wire 24, back contact 25-25^a of relay A, wire 26, contact 23-23² of lever L, wires 33, 34 and 35, contact 22-22^a of pressure responsive device P²⁰⁻³⁰, wires 36, 37 and 38, winding 12 of valve V², and wire 32 back to battery C. Valve V¹ therefore becomes deenergized and valve V² becomes energized. The deenergization of valve V¹ disconnects pipe 14 from port 15, and connects pipe 14 with pipe 16, while the energization of valve V² connects pipe 17 with pipe 16. As a result, fluid at full line pressure is now supplied to the right-hand end of cylinder 4 of motor M, thus causing the braking bars to move to their effective or braking positions. As soon as the pressure of the fluid in the right-hand end of cylinder 4 of motor M reaches 20 pounds per square inch, contact 22-22^a of pressure responsive device P²⁰⁻³⁰ will open and will interrupt the circuit just traced for valve V². Valve V² will then become deenergized and will cut off the supply of fluid to the right-hand end of cylinder 4 until the pressure in the motor again decreases below 20 pounds per square inch, at which time valve V² will again become energized, and will again admit fluid to the right-hand end of cylinder 4. If the fluid in the right-hand end of cylinder 4 of motor M now increases to a pressure of 30 pounds per square inch for any reason, contact 22-22^b of pressure responsive device P²⁰⁻³⁰ will become closed and will complete a circuit for valve V¹, which circuit passes from battery C through wire 24, back contact 25-25^a of relay A, wire 26, contact 23-23² of lever L, wires 33, 34 and 35, contact 22-22^b of pressure responsive device P²⁰⁻³⁰, wires 29, 30 and 31, winding 12 of valve V¹, and wire 32 back to battery C. Valve V¹ will therefore become energized and will vent fluid from cylinder 4 until the pressure again decreases to 30 pounds per square inch, at which time contact 22-22^b will open and deenergize valve V¹. It will be seen, therefore, that when relays A and B are both deenergized and lever L occupies its p² position, the braking bars will be held in their braking positions by a pressure of between 20 and 30 pounds per square inch.

40 I will now assume that lever L occupies its p³ position and that relay A becomes energized. Under these conditions all circuits which were previously closed for the valves V¹ and V² will be interrupted, and a circuit for valve V¹ will become completed which passes from battery C through wire 24, front contact 25-25^b of relay A, wires 39, 28, 29, 30 and 31, winding 12 of valve V¹, and wire 32 to battery C. Valve V¹ will therefore become energized and will vent fluid from the right-hand end of motor M, thus permitting the biasing means to return the braking bars to their non-braking positions in which they are shown in the drawings.

50 If relay B becomes energized when lever L occupies its p³ position, all parts will remain in the positions which they previously occupied since none of the circuits for the valves V are controlled by this relay in this position of lever L.

55 I will now assume that the relays A and B are both deenergized and that the operator moves the lever L to its p⁴ position. Under these conditions, valve V¹, if it is not already deenergized, will become deenergized, and valve V² will become energized over a circuit which passes from battery C through wire 24, back contact 25-25^a of relay A, wire 26, contact 23-23³ of lever L, wire 40, back contact 41-41^a of relay B, wire 42, contact 22-22^a of pressure responsive device P⁴⁵⁻⁵⁵, wires 70 75

37 and 38, winding 12 of valve V², and wire 32 back to battery C. Fluid pressure will therefore now be admitted to the right-hand end of cylinder 4 of motor M until the pressure of the fluid in 5 the cylinder increases to 45 pounds per square inch, at which time contact 22—22^a of pressure responsive device P^{45—55} will open and will de-energize valve V². If the pressure in the right-hand end of cylinder 4 now increases to 55 pounds 10 per square inch, contact 22—22^b of pressure responsive device P^{45—55} will become closed and will complete another circuit for valve V¹, this latter circuit passing from battery C through wire 24, back contact 25—25^a of relay A, wire 26, contact 15 23—23^b of lever L, wire 40, back contact 41—41^a of relay B, wire 42, contact 22—22^b of pressure responsive device P^{45—55}, wires 30 and 31, winding 12 of valve V¹, and wire 32 to battery C. Valve V¹ will therefore become energized and will ex-20 haust fluid from the right-hand end of cylinder 4 until the pressure decreases to that at which contact 22—22^b of pressure responsive device P^{45—55} opens. It will be apparent, therefore, that when lever L occupies its p³ position, the braking bars 25 will be held in their braking positions by a pressure of between 45 and 55 pounds per square inch.

If when lever L occupies its p³ position relay A becomes energized, all circuits which were previously closed for the valves V¹ and V² will be come interrupted and the previously described circuit for valve V¹ including front contact 25—25^b of relay A will become closed, thus causing the braking bars to move to their non-braking positions in the manner previously described.

If when lever L occupies its p³ position, relay B becomes energized, all circuits which were previously closed for the valves V¹ and V² will become interrupted, and a circuit for valve V¹ will become closed, which circuit is similar to the circuit which becomes closed for this valve when relays A and B are both deenergized and lever L occupies its p² position, with the exception that this latter circuit includes, instead of contact 23—23^a of lever L and wire 33, contact 23—23^b of lever L, wire 40 and front contact 41—41^b of relay B. When this circuit becomes closed, fluid will be vented from the right-hand end of cylinder 4 of motor M until the pressure in this end of the cylinder decreases to 30 pounds per square inch at which time the resultant opening of contact 22—22^b of pressure responsive device P^{20—30} will interrupt the circuit which was previously closed for valve V¹ at this contact, thus deenergizing this valve, and hence preventing further exhaust of fluid to atmosphere. If while relay B is energized the pressure in the right-hand end of motor M decreases to that at which contact 22—22^a of pressure responsive device P^{20—30} becomes closed, valve V² will then become energized over a circuit which is similar to that over which this valve becomes energized when the relays A and B are both deenergized and lever L occupies its p² position, with the exception that this latter circuit includes contact 23—23^b of lever L, wire 40, and front contact 41—41^a of lever L instead of contact 23—23^a of lever L, and wire 33. It will be seen, therefore, that if relay B becomes energized when lever L occupies its p³ position, the pressure in the right-hand end of cylinder 4 of motor M will decrease to that corresponding to the p² position of lever L, and will be subsequently maintained at this pressure as long as relay B remains energized and lever L remains in its p³ position.

75 I will now assume that the relays A and B are both deenergized and that the operator moves lever L to its p⁴ position. Under these conditions, valve V² will become energized over a circuit which passes from battery C through wire 24, back contact 25—25^a of relay A, wire 26, contact 23—23^b of lever L, wire 40, back contact 41—41^a of relay B, wire 42, contact 22—22^a of pressure responsive device P^{70—80}, wire 38, winding 12 of valve V² and wire 32 to battery C. Fluid will therefore now be supplied to the right-hand end of cylinder 4 until the pressure in this end of the cylinder reaches 70 pounds per square inch, which is the pressure at which contact 22—22^a of pressure responsive device P^{70—80} opens. If the pressure in the right-hand end of cylinder 4 now increases to 80 pounds per square inch, contact 22—22^b of pressure responsive device P^{70—80} will become closed and will complete still another circuit for valve V¹. This latter circuit for valve V¹ may be traced from battery C through wire 24, back contact 25—25^a of relay A, wire 26, contact 23—23^b of lever L, wire 40, back contact 41—41^a of relay B, wire 42, contact 22—22^b of pressure responsive device P^{70—80}, wire 34, winding 12 of valve V¹ and wire 32 back to battery C. Valve V¹ will therefore become energized until the pressure in the right-hand end of cylinder 4 decreases to 80 pounds per square inch. It will be seen, therefore, that when relays A and B are both deenergized and lever L occupies its p⁴ position, the right-hand end of cylinder 4 of motor M will be supplied with fluid at a pressure of between 70 and 80 pounds per square inch, so that the braking bars will exert a corresponding braking force.

If with lever L in its p⁴ position relay A becomes energized, both circuits which were previously closed for valves V¹ and V² in this position of the lever will become interrupted and valve V¹ will become energized over the previously described circuit for this valve including front contact 25—25^b of relay A. It follows, therefore, that under these conditions the braking bars will again be moved to their non-braking positions by the biasing means 20.

If when lever L occupies its p⁴ position relay B becomes energized, the opening of back contact 44—44^a of relay B will interrupt the circuits which were previously closed for either valve V¹ or V² while the closing of the front contact 44—44^b of this relay will complete another circuit for valve V¹ or another circuit for valve V² according as contact 22—22^b or contact 22—22^a of pressure responsive device P^{20—30} is then closed. These latter circuits for the valves V¹ and V² are similar to those which are closed for these valves when lever L occupies its p² position, with the exception that these circuits each includes contact 23—23^b of lever L, wire 40, front contact 44—44^b of lever L and wire 41 in place of contact 23—23^a of lever L and wires 33 and 34. It will be seen, therefore, that if relay B becomes energized when lever L occupies its p⁴ position, the pressure in the right-hand end of cylinder 4 of motor M will be reduced to the same pressure which is maintained in this motor when lever L occupies its p² position.

I will now assume that relays A and B are both deenergized and that lever L is moved to its p⁵ position. Under these conditions valve V² will become energized and will subsequently remain energized over a circuit which passes from battery C through wire 24, back contact 25—25^a of relay A, wire 26, contact 23—23^b of lever L, wire 40, back contact 49—49^a of relay A, wires 50, 36, 37 and 38, winding 12 of valve V², and wire 32 back to battery C. It will be apparent, therefore, that

under these conditions, the braking bars will be held in their braking positions by fluid at full line pressure.

If, when lever L occupies its p^5 position, relay A becomes energized, the braking bars will again be moved to their non-braking positions in the manner previously described. If, however, under these conditions, relay B becomes energized, the opening of back contact 49-49^a of relay B will 10 interrupt the circuit which was then closed for valve V¹ or V², as the case may be, and will close another circuit for valve V¹. This circuit is similar to that which was closed for this valve in the p^4 position of the lever when the pressure in the 15 right-hand end of the cylinder was greater than 80 pounds per square inch, with the exception that this circuit includes contact 23-23⁵ of lever L, wire 48, and front contact 49-49^b of relay B instead of contact 23-23⁴ of lever L, wire 43, and 20 back contact 44-44^a of relay A. Valve V¹ will therefore become energized and will vent fluid from the right-hand end of cylinder 4 of motor M until the pressure in this end of the cylinder decreases to 80 pounds per square inch at which time 25 the resultant opening of contact 22-22^b of pressure responsive device P⁷⁰⁻⁸⁰ will deenergize valve V¹. If the pressure in the right-hand end of cylinder 4 of motor M further decreases to 70 pounds 30 per square inch under the conditions just described so that contact 22-22^a of pressure responsive device P⁷⁰⁻⁸⁰ becomes closed, valve V² will become energized and will admit fluid to the right-hand end of cylinder 4 of motor M by virtue of a circuit which is similar to that which is closed 35 for this valve under corresponding conditions when lever L occupies its p^4 position with the exception that this circuit includes contact 23-23⁵ of lever L, wire 48, and front contact 49-49^b of relay B instead of contact 23-23⁴ of lever L, wire 43, and back contact 44-44^a of relay B.

It should be observed that if, when relays A and B are both deenergized, the operator moves lever L from a position corresponding to a higher braking force to a position corresponding to a lower 45 braking force, the apparatus will immediately and automatically reduce the braking pressure to a value corresponding to the new position of the lever in a manner which will be apparent from the drawings without tracing the sequence of operation in detail.

When relays A and B are both deenergized and lever L occupies any one of its p^2 , p^3 , p^4 or p^5 positions, so that the braking bars occupy their braking positions, and the operator wishes to restore the braking bars to their non-braking positions in which they are illustrated in the drawings, he will restore lever L to its p^1 or "off" position. When he does this, all circuits previously traced for valve V² will be interrupted, and the 55 circuit previously described for valve V¹ including contact 23-23¹ of lever L will become closed. Valve V² will therefore become deenergized and valve V¹ will become energized. As a result, the supply of fluid pressure to the right-hand end of cylinder 4 of motor M will be cut off and the fluid which was previously supplied to this end of the cylinder will be vented to atmosphere. The braking bars will therefore move, due to the bias of spring 20, to their ineffective or non-braking 60 positions. When the braking bars reach their non-braking positions, all parts will be restored to the positions in which they are shown in the drawings.

The previously mentioned speed responsive apparatus for controlling the relays A and B com-

prises a series of relatively short insulated control sections 51^a, 51^b, etc. which are formed in the rail 1. These control sections will usually be of uniform length and their lengths may be varied as conditions require, but the lengths of these sections will preferably be such that two wheels of a car can not occupy the same section at any one time.

The speed responsive means for controlling relays A and B also includes a speed control lever S 10 which, as here shown, is capable of assuming three positions, designated s^1 , s^2 and s^3 , respectively, in the drawings, and which is provided with three contacts 52, 53 and 54. Contacts 52 and 53 are so arranged that these contacts will 15 be closed when and only when the lever occupies its s^3 position, and contact 54 is so arranged that this contact will be closed in any position of the lever except its s^1 or off position.

Associated with each control section 51 is a 20 track relay designated by the reference character D with a suitable distinguishing exponent, two resistors each designated by the reference character R with a distinguishing exponent and subscript, and two timing relays each designated by 25 the reference character T with a suitable distinguishing exponent and subscript.

The track relays D^a, D^b, D^c, etc. are similar relays, and as here shown, each of these relays is connected in a track circuit which includes, in 30 addition to the associated control section 51, the rail 1^a, contact 54 of speed control lever S, and a suitable source of current here shown as a battery F. It will be apparent, therefore, that when contact 54 of lever S is open, or when this contact is closed and all of the sections 51 are unoccupied, all of the track relays D will be deenergized, but that, when contact 54 is closed, and a car wheel moves onto any one of the sections 51 the associated track relay D will become energized. 40 It will also be apparent that the duration of the time interval during which a track relay remains energized when it has once become energized will depend upon the time required for a car to traverse a distance which is equal to the length of the 45 associated control section, and hence upon the speed of the car.

The timing relays T₁^a, T₁^b, T₁^c, etc. are also similar relays, and as here shown, each of these relays has a release time which is equal to that 50 required for a car to traverse a distance equal to the length of one of the control sections 51 when the car is traveling at the maximum control speed at which it is desired to have the car leave the retarder. For example, for purposes of illustration I will assume that each relay T₁ is adjusted to have a release time which is equal to that required for a car traveling at 7 miles per hour to traverse the distance equal to the length of one 55 of the control sections 51. Each relay T₁ is provided with a pickup circuit which includes the winding of the relay, back contact 55-55^a of the associated track relay D, a wire 63, a battery E, and a wire 62.

The timing relays T₂^a, T₂^b, T₂^c, etc. are likewise 65 similar relays, and each of these relays is constructed to have a release time which is equal to the time required for a car to traverse one of the sections 51 when the car is traveling at a speed which is slightly higher than the maximum control speed. For example, assuming that the maximum control speed is 7 miles per hour, each timing relay T may be adjusted to have a release time which is equal to that required for a car traveling 70 at 8 miles per hour to traverse a distance equal 75

to the length of one of the control sections 51. Each timing relay T₂ is provided with a pickup circuit which includes the winding of the relay, a back contact 58—58^a of the associated track relay D, a wire 59, a battery J, and a wire 60.

With the timing relays controlled in the manner thus far described it will be apparent that when none of the track relays D are energized, as is the case when contact 54 of lever S is open, or when this contact is closed and no car is traversing the stretch of track shown in the drawings, all of the timing relays T will be energized, but that, when contact 54 is closed and a car is traversing the stretch of track shown in the drawings, each time a car wheel moves onto one of the control sections 51 and causes the associated track relay D to become energized, the timing relays controlled by such track relay will become de-energized and will remain deenergized for a time interval which depends upon the speed of the car. It follows that if the speed of the car is less than 8 miles per hour but greater than 7 miles per hour, the associated timing relay T₂ will release its armature and close its back contact 65 and that, if this car speed is less than 7 miles per hour, both the associated timing relay T₂ and the associated timing relay T₁ will release their armatures and will close their back contacts 65 and 66, but that, if the speed of the car is above 8 miles per hour, neither of the associated timing relays will release its armature.

For reasons which will be made clear as the description proceeds, it is desirable to be able to at times vary the release times of the timing relays T to cause them to close their back contacts at different car speeds, and for this purpose each of the timing relays T₁ is provided with a shunt circuit which includes the associated resistor R₁, while each of the timing relays T₂ is provided with a similar control circuit which includes the associated resistor R₂. Referring particularly to the timing relays T_{1a} and T_{2a}, the shunt circuit for the relay T_{1a} includes front contact 55—55^b of track relay D^a, resistor R_{1a}, wire 64, contact 53 of lever L, and wire 62, while the shunt circuit for the timing relay T_{2a} includes front contact 58—58^b of relay D^a, resistor R_{2a}, wire 61, contact 52 of lever S, and wire 60. The shunt circuits for each of the other timing relays are similar to those just described for the timing relays T_{1a} and T_{2a}.

It will be readily understood that if more than two release times are desired for each timing relay, these relays may be provided with additional shunt circuits, each similar to the shunt circuits shown but each having a different resistance and so arranged that different ones of these circuits may be rendered effective by moving lever S to different positions. It will also be readily understood that the release times of the timing relays T when the shunt circuits shown are cut in may be regulated to any desired value within the limits of design of these relays by choosing the proper value of the resistance for the associated resistor R. As here shown, the resistances of the resistors R₂ are such that when these resistances are cut in, the relays T₂ will release at all car speeds below 5½ miles per hour, and the resistances of the resistors R₁ are such that when these resistors are cut in, the associated relays T will release at all car speeds below 4 miles per hour.

The slow releasing relays T₂ control relay B by virtue of a plurality of parallel pickup circuits, each of which includes a suitable source of current here shown as a battery G, and the front contact 65 of a different one of the timing relays

T₂. It will be seen, therefore, that when all of the timing relays T₂ are energized, relay B will be deenergized, but that when any one of the timing relays T₂ becomes deenergized and remains deenergized for a sufficient interval of time to cause it to close its back contact 65, relay B will become energized.

Relay B is made sufficiently slow releasing so that, when a car is traversing the stretch of track shown in the drawings at a speed which is just slow enough to cause the timing relays T₂ to successively close their back contacts 65, this relay will bridge the interval of time which will elapse under these conditions between the opening of the back contact 65 of one timing relay T₂ due to a wheel of the car having departed from the associated section 51, and the closing of the back contact 65 of the timing relay T₂ next in advance due to the same wheel of the car having moved onto the section 51 associated with this latter timing relay.

The slow releasing relays T₁ control relay A by virtue of a plurality of pickup circuits each of which includes a suitable source of current, here shown as a battery H and the back contact 66 of a different one of the timing relays T₁. It will be seen, therefore, that when all of the timing relays T₁ are energized, relay A will be deenergized, but that when any one of the timing relays T₁ becomes deenergized and remains deenergized for a sufficient interval of time to cause it to close its back contact 66, relay A will become energized.

Relay A is made sufficiently slow releasing so that, when a car is traversing the stretch of track shown in the drawings at a speed which is just slow enough to cause the timing relays T₁ to successively close their back contacts 66, this relay will bridge the interval of time which will elapse under these conditions between the opening of the back contact 66 of one timing relay due to a wheel of the car having departed from the associated section 51, and the closing of the back contact 66 of the timing relay T₁ next in advance due to the same wheel of the car having moved onto the section 51 associated with this latter timing relay.

As shown in the drawings, all parts of the apparatus are in the positions which they normally occupy when no car is traversing the stretch of track shown in the drawings. That is to say, the track relays D are all deenergized, the timing relays T are all energized, speed control lever S occupies its s¹ position, relays A and B are both deenergized, and lever L occupies its p¹ or off position. Under these conditions, the braking bars are, of course, held in their non-braking positions.

In explaining the operation of the apparatus as a whole, I will first assume that a car which is moving at a speed of more than 8 miles per hour is approaching the stretch of track shown in the drawings, and that it is desired to have the car leave the retarder at a speed of 7 miles per hour. The operator, therefore, first moves lever L to a position which will cause the braking bars to exert sufficient braking force to slow down the car the necessary amount. That is to say, if the car is a light weight car, he moves lever L to its p² position, if the car is a medium weight car, he moves lever L to its p³ or p⁴ position, and if the car is a heavy car, he moves lever L to its p⁵ position. When this lever is moved to any one of these positions, fluid pressure is, of course, admitted to cylinder 4 in the manner previously described to move the braking bars to their effec-

tive or braking positions. The operator next moves the speed control lever S to its s^2 position, which is the position corresponding to a leaving speed or control speed of 7 miles per hour. As 5 the car moves through the retarder, each time a wheel of the car moves onto one of the control sections 51, the associated track relay D will become energized and will deenergize the associated timing relays T_1 and T_2 , but as long as the speed 10 of the car is above 8 miles per hour, none of the timing relays T_1 or T_2 will remain deenergized long enough to close its back contact 66 or 65. Relays A and B will therefore both remain deenergized and the car retarder will therefore 15 continue to slow down the car. As soon, however, as the car has been slowed down by the car retarder to a speed which is equal to or less than 8 miles per hour, and a wheel of the car traverses one of the control sections 51, the associated timing 20 relay T_2 will close its back contact 65, and relay B will then become energized. When relay B becomes energized, the pressure of the fluid supplied to cylinder 4 of motor M will become decreased in the manner previously described so 25 that the braking force exerted by the braking bars will then be less than that which was previously exerted by the braking bars. The braking bars, however, will continue to slow down the car until the car speed decreases to 7 miles per 30 hour. When this happens, as soon as a wheel of the car traverses one of the control sections 51, the associated timing relay T_1 will then become deenergized and will close its back contact 66, thus causing relay A to become energized. The 35 energization of relay A will cause the braking bars to move to their non-braking positions in the manner previously described, and it will be apparent, therefore, that no further retardation of the car will take place unless relay A again becomes deenergized and remains deenergized for a sufficient interval of time to cause it to open 40 its front contact 25-25^b and close its back contact 25-25^a while the car is still within the limits of the car retarder. Due to the slow releasing 45 characteristics of relay A previously pointed out, this can only happen in the event that the car accelerates to a speed which is greater than 7 miles per hour. Assuming the car does this, then as soon thereafter as the timing relay T_1 which 50 last became deenergized for a time interval of sufficient duration to cause it to close its back contact 66 again becomes energized, relay A will become deenergized and will subsequently remain deenergized, because under these 55 conditions, none of the timing relays T_1 will now become deenergized long enough to close its back contact 66. Relay A will therefore open its front contact 25-25^b and will close its back contact 25-25^a, thus restoring the braking bars to their 60 braking positions. If, when the braking bars are restored to their braking positions the car speed is then below 8 miles per hour, none of the timing relays T_2 will then be energized so that relay B will be energized and the braking bars will therefore 65 exert the same braking force which they exerted when the car speed decreased below 8 miles per hour. If, however, when the braking bars are restored to their braking positions the car speed is then above 8 miles per hour, or subsequently increases to a speed which is greater 70 than 8 miles per hour, so that none of the timing relays T_2 are then energized, relay B will then be deenergized and the braking bars will then exert a braking force corresponding to the position which lever L then occupies.

I will now assume that with the braking bars in their braking positions, the operator moves speed control lever S to its s^3 position instead of its s^2 position, in order to slow down a car which is approaching the retarder at a relatively high 5 speed to the lowest speed for which the apparatus is designed. Under these conditions, the operation of the apparatus will be similar to that just described with the exception that since contacts 52 and 53 of lever S are now closed, when 10 a track relay D becomes energized and deenergizes the associated timing relays T_1 and T_2 , it will at the same time complete the shunt circuit for the associated timing relays, thus increasing the length of time these relays must be deenergized before they will close their back contacts. It will be seen, therefore, that when lever S occupies its s^3 position, the timing relays T_2 and T_1 will then release their armatures at a car speed of 5 and 4½ miles per hour, respectively, 15 with the result that the braking force exerted on the car will become decreased when the car speed decreases to 5½ miles per hour, and the braking bars will be automatically moved to their non-braking positions when the car speed has 20 been decreased to 4 miles per hour.

Referring now to Fig. 2, as here shown, the valves V^1 and V^2 , instead of being controlled in part by relay A in the manner shown in Fig. 1, are controlled in part by two relays A^1 and A^2 in 30 such manner that, when both of these relays are deenergized, the operation of the valves V^1 and V^2 for all positions of lever L will be the same as the operation of these valves in Fig. 1 when relay A is deenergized; and that, when either 35 one of these relays becomes energized, the operation of these valves for all positions of lever L will then be the same as the operation in Fig. 1 when relay A becomes energized. The circuits over which the valves V^1 and V^2 are controlled 40 when relays A^1 and A^2 are both deenergized are similar to the corresponding circuits over which these valves are controlled in Fig. 1 when relay A is deenergized, with the exception that each 45 of these circuits includes in place of back contact 25-25^a of relay A, a back contact 25-25^a of relay A^1 , and a back contact 25-25^a of relay A^2 , connected in series; and the circuit over which 50 valve V^1 is controlled when relay A^1 becomes energized is similar to that over which this valve 55 is controlled in Fig. 1 when relay A becomes energized, with the exception this this circuit includes in place of front contact 25-25^b of relay A, front contact 25-25^b of relay A^1 ; while the 60 circuit over which valve V^1 is controlled in Fig. 2 when relay A^2 becomes energized is similar to that over which valve V^1 is controlled in Fig. 1 when relay A becomes energized, with the exception that this latter circuit includes in place of front contact 25-25^b of relay A, back contact 65 25-25^a of relay A^1 and front contact 25-25^b of relay A^2 . It is believed that since the circuits over which the valves V^1 and V^2 are controlled in Fig. 2 differ from those over which these valves are controlled in Fig. 1 only in the manner just 70 pointed out, these circuits will be apparent from the foregoing description and from an inspection of the drawings without further detailed description. It is also believed that since the operation of the valves for all positions of lever L in Fig. 2 is similar to that described in connection with Fig. 1 except for the differences above pointed out, the operation of these valves when lever L is moved to its different positions will be under- 75

stood from the foregoing and from an inspection of the drawings without further description.

Referring now to the speed responsive means for controlling the relays B, A¹ and A², this means in the form here shown comprises a plurality of track relays D₁^a, D₁^b, etc. one of which is associated with each control section 51 but the last, and a track relay D^e which is associated with the last control section. The relays D₁^a, D₁^b, etc. 10 are similar relays, and each of these relays is provided with two opposing magnets 70 and 71 which jointly control a back contact 55-55^a and three front contacts 55-55^b, 72 and 73. The magnet 70 of each relay D₁ is more powerful than the magnet 71, and the parts are so proportioned 15 that, when the magnet 70 of a relay becomes energized, the relay will open its back contact and close its front contacts, and that, after the magnet 70 of a relay once becomes energized the back contact of the relay will remain open and the front contacts will remain closed until the magnet 70 again becomes deenergized, even though the magnet 71 subsequently becomes energized. The function of the magnet 71 will 20 become apparent as the description proceeds.

The winding of each magnet 70 is connected in a track circuit which includes in addition to the associated control section 51, the rail 1^a, contact 54 of lever S and a battery F. The winding 30 of each magnet 71 with the exception of the magnet 71 of relay D₁^f is provided with a pickup circuit which includes the front contact 73 of the associated relay, the front contact 72 of the relay next in advance, a common wire 74, battery F and a common wire 75. The winding of magnet 71 of relay D₁^f is provided with a pickup circuit which includes the front contact 73 of relay D₁^f, front contact 72 of relay D^e, common wire 74, battery F and common wire 75.

40 Track relay D^e is similar to the relays D^a, D^b, etc. shown in Fig. 1, and is provided with a track circuit which is similar to that for the magnet 70 of each of the relays D₁^a, D₁^b, etc.

With the track relays D₁^a, D₁^b, etc. arranged in the manner just described, it will be apparent that, when contact 54 of lever S is open, or when this contact is closed and no car is traversing the stretch of track shown in the drawings, the magnets 70 and 71 of each of the relays D₁^a, D₁^b, etc. 45 will be deenergized, and relay D^e will also be deenergized. When, however, contact 54 of lever S is closed, each time a car wheel moves onto any one of the sections 51 but the section 51^e, the magnet 70 of the associated track relay will 50 become energized, and will subsequently remain energized, until the car wheel leaves the section, and each time a car wheel moves onto the section 51^e, the track relay D^e will become energized and will subsequently remain energized until the car 55 wheel departs from this section. When the magnet 70 of a track relay becomes energized, the relay will open its back contact and close its front contacts, and when the magnet 70 subsequently becomes deenergized, the relay will ordinarily 60 immediately open its front contacts and close its back contact. If, however, a relay fails to open its front contacts and close its back contact immediately when the car wheel leaves the associated section 51, due, for example, to leakage current supplied to the magnet 70, or to residual magnetism, then as soon thereafter as the relay 65 next in advance closes its front contact 72, the circuit for the magnet 71 of the relay which failed to open its front contacts will become closed and 70 will thus cause this magnet to become energized,

and the energization of this magnet will pull the front contacts open, thus causing the front contacts to open almost as quickly as they would have opened if there had been no leakage current or residual magnetism. A similar action 5 will take place if relay D₁^f has not opened its front contacts when relay D^e becomes energized. If the magnet 70 of a track relay becomes energized while the magnet 70 of the relay next in advance is energized, the resultant closing of the 10 circuit for the magnet 71 of the relay in rear will not affect the relay in rear, since the magnet 71 is not strong enough to cause the relay to open its front contacts under these conditions, and the fact that the magnet 71 for the relay in the rear 15 is energized will assist in causing such relay to open its front contacts quickly when its magnet 70 subsequently becomes deenergized. It follows, therefore, that with the relays D₁ constructed and arranged in the manner shown in Fig. 2, 20 these relays will operate without lag, and the time interval during which the front contacts of the relays remain closed and the back contacts remain open will depend positively on the speed 25 of the car.

Associated with each track relay D₁ is a timing relay designated by the reference character T with a suitable distinguishing exponent. The timing relays T^a, T^b, etc. are similar to the relays T₂^a, T₂^b, etc. shown in Fig. 1 and have the same 30 slow releasing characteristics as the relays T₂^a, T₂^b, etc. Each timing relay T as shown in Fig. 2 is provided with a pickup circuit which includes a back contact 55-55^a of the associated track relay D₁, wire 63, battery E, and wire 62. Each timing relay T is also provided with a shunt circuit which includes front contact 55-55^b of the associated track relay D₁, an associated one of a plurality of resistors R, wire 64, contact 53 of lever L, and a wire 62. It will be seen, therefore, that when 40 none of the magnets 70 of the track relays D are energized, as when contact 54 of lever S is open, or when contact 54 is closed and no car is traversing the stretch of track shown in the drawings, all of the timing relays T will be energized; but 45 that, when contact 54 of lever S is closed and a car is traversing the stretch of track shown in the drawings, each time a car wheel moves onto one of the control sections 51, and causes the magnet 70 of the associated track relay D to become energized, the timing relay controlled by such track relay will become deenergized for a time interval which depends upon the speed of the car. If the speed of the car is sufficiently 50 slow so that this time interval is longer than the release time of such timing relay T, this timing relay will close its back contact 65, but if the speed of the car is not sufficiently slow so that this time interval is longer than the release time of this timing relay, this timing relay will not close its back contact 29. The release times of the timing relays T depend upon whether speed control lever S occupies its s² or s³ position, and it follows that these relays will close their back contacts at one car speed when the lever S occupies its s² position and at another car speed when the lever S occupies its s³ position. 55

Relay B is controlled by the timing relays T^a, T^b, etc. in exactly the same manner that this relay is controlled by the timing relays T₂^a, T₂^b, etc. in 70 Fig. 1.

Relay A¹ is controlled by the timing relays T^a, T^b, T^c, etc. and by lever S by virtue of a plurality of pickup circuits each of which includes a battery G, a back contact 65 of a different one of 75

the timing relays and a contact 52—52³ of lever S. It will be seen, therefore, that when lever S occupies either its s¹ or its s² position or when all of the timing relays T^a, T^b, etc. are energized, 5 relay A¹ will be deenergized, but that when lever S is moved to its s³ position and any one of the timing relays becomes deenergized and remains deenergized for a sufficient interval of time to close its back contact 65, relay A¹ will become 10 energized. Due, however, to the slow pickup characteristics of this relay previously pointed out, this relay will not open its back contact 25—25^a and close its front contact 25—25^b unless the back contact 65 which causes this relay to 15 become energized remains closed for a time interval which is longer than the pickup time of this relay. Relay A¹ is made sufficiently slow releasing so that, when a car is traversing the stretch of track shown in the drawings at a 20 speed which is just slow enough to cause the timing relays T to successively close their back contact 65 when the lever S occupies its s³ position, this relay will bridge the interval of time which will elapse under these conditions between 25 the opening of the back contact 65 of one timing relay due to a wheel of the car having departed from the associated control section 51, and the closing of the back contact 65 of the timing relay T next in advance due to the same wheel of the 30 car having moved onto the section 51 associated with this latter timing relay.

Relay A² is likewise controlled by the timing relays T^a, T^b, T^c, etc. and by lever S by virtue of a plurality of parallel pickup circuits each of 35 which includes battery G, a back contact 65 of a different one of the timing relays T and contact 52—52² of speed control lever S. It will be seen, therefore, that when lever S occupies either its s¹ or s³ positions or when all of the timing relays 40 T are energized, relay A² will be deenergized, but that, when lever S occupies its s² position and any one of the relays T becomes deenergized and closes its back contact 65, relay A² will become energized but will not open its back contact 45 25—25^a and close its front contact unless the contact 65 which causes this relay to become energized remains closed for a time interval which is longer than the pickup time of this relay. Relay A² is made sufficiently slow releasing so that, 50 when a car is traversing the stretch of track shown in the drawings at a speed which is just slow enough to cause the timing relays T to successively close their back contacts 65 when lever S occupies its s² position, this relay will bridge 55 the interval of time which will elapse under these conditions between the opening of the back contact 65 of one timing relay due to the wheel of the car having departed from the associated control section 51, and the closing of the back contact 60 65 of the timing relay T next in advance due to the same wheel of the car having moved onto the section 51 associated with this latter timing relay.

As shown in the drawings, all parts of the apparatus are in the positions which they normally occupy when no car is traversing the stretch of track shown in the drawings. That is to say, the magnets 70 and 71 of the timing relays T¹ are all deenergized, track relay D^g is deenergized, the timing relays T are all energized, speed control lever S occupies its s¹ position, relays B, A¹ and A² are all deenergized, lever L occupies its p¹ position, valve V¹ is energized and valve V² is deenergized. With valve V¹ energized and valve V² 75 deenergized the braking bars are held in their

non-braking positions by the biasing spring 20.

In explaining the operation of the apparatus as a whole I will assume that a car is approaching the car retarder from the left at a relatively high speed that the operator wishes to slow the car down to a speed corresponding to the s² position of the speed control lever. To do this, he will move the lever L to the proper braking position in the manner previously described and will move the speed control lever S to its s² position. As the car moves through the retarder, each time a wheel of the car moves onto one of the control sections 51, the magnet 70 of the associated track relay D¹ will become energized and will deenergize the associated timing relay T, but as long as the speed of the car is above the speed at which the timing relays T are adjusted to release their armatures, which speed is somewhat higher than that corresponding to the s² position of the lever, the relays B, A¹ and A² will all remain deenergized and the car retarder will continue to slow down the car. As soon, however, as the car has been slowed down by the car retarder to the speed at which the timing relays T are adjusted to release their armatures and a wheel of the car traverses one of the control sections 51, the associated relay T will close its back contact 65 and, when this happens, the pickup circuits for relay B and relay A¹ controlled by such contact will become closed. Relay B will therefore immediately pick up, which will cause the braking force exerted by the braking bars to decrease in the manner described in connection with Fig. 1. Relay A¹, however, will not pick up until the car has been slowed down to the control speed corresponding to the s² position of the speed control lever S, and a car wheel has traversed one of the control sections 51, because, for all speeds above this control speed, none of the contacts 65 of the timing relays T will remain closed for a time interval which is equal to or greater than the pickup time for this relay. If, however, the car has slowed down to this control speed, relay A¹ will then pick up and the braking bars will then be moved to their non-braking positions in the manner previously described, and under these conditions no further retardation of the car will take place unless relay A¹ again becomes deenergized and remains deenergized for a time interval which is sufficiently long to cause this relay to release its armature while the car is still within the limits of the retarder. Due to the slow release characteristics of relay A¹ previously pointed out, this can only happen in the event that the car accelerates to a speed which is greater than that corresponding to the s² position of the speed control lever S. Assuming that the car does this, then as soon thereafter as the timing relay T which last became deenergized for a time interval of sufficient duration to cause relay A¹ to pick up its armature again becomes energized, relay A¹ will again become deenergized, and its armature will subsequently remain open, because, under these conditions, none of the other timing relays will now become deenergized for a long enough interval of time to cause relay A¹ to again close its armature. Relay A¹ will therefore open its front contact 25—25^b and close its back contact 25—25^a thus restoring the braking bars to the braking positions. The braking bars, however, will not exert the full braking force corresponding to the position which the lever then occupies unless the car speed has increased to a speed at which none of the timing relays will close their back 75

contact 65, because as long as the speed of the car is below this speed, relay B will become energized each time a timing relay closes its back contact and as long as this relay remains energized the braking bars will exert a reduced braking force on the car. If, however, the car speed does increase above that at which the relays T^a close their back contacts 65, relay B will then become deenergized and the braking bars will then 10 exert their full braking force corresponding to the position which the lever L then occupies.

I will now assume that with the braking bars in their braking positions, the operator moves lever S to its s³ position instead of its s² position, 15 in order to slow down a car which is approaching the retarder at a relatively high speed to the slowest speed for which the apparatus is designed. Under these conditions, the operation of the apparatus will be similar to that just described with the exception that, under these conditions, the shunt circuits for the timing relays will now be rendered effective, so that these relays will release their armatures at a slower car speed, and with the further exception that the 25 relay A² will now be effective for controlling the braking apparatus instead of the relay A¹. As was previously pointed out, the relay A² has a slower pickup time than the relay A¹ and it will be apparent, therefore, that when lever S occupies its p³ position, the retarder will slow down the car to a lower car speed, as will readily be understood from the foregoing without further description.

One advantage of braking apparatus embodying my invention is that the retardation force exerted by the apparatus, and thereby the rate of retardation of a car which is being retarded by the apparatus, is decreased as the speed of the car approaches control speed, thus permitting 35 full release of the retarder at a value nearer that of the nominal control speed after the car speed has actually reached control speed. The effect of this operation is to cause a more accurate control of the car speed, since this control is dependent, to a large extent, upon the length of time required to fully release the retarder, and the rate of retardation during this release. This is particularly important when the full braking force is applied to a car at a low control speed. 45

50 Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a stretch of railway track, fluid pressure operated braking apparatus for 55 retarding the speed of a car traversing said stretch, means for supplying said apparatus with fluid at different pressures to cause said apparatus to exert different braking forces, and means controlled by the speed of a car traversing said stretch for reducing the pressure of the fluid supplied to said apparatus a first predetermined amount when the speed of the car has decreased to a predetermined speed and for subsequently reducing said pressure a second predetermined 70 amount.

2. In combination, a stretch of railway track, fluid pressure operated braking apparatus for 75 retarding the speed of a car traversing said stretch, means for supplying said apparatus with fluid at different pressures to cause said appa-

ratus to exert different braking forces, and means controlled by the speed of a car traversing said stretch for reducing the pressure of the fluid supplied to said apparatus a first predetermined amount when the speed of the car has 5 decreased to a first predetermined speed and for subsequently reducing said pressure a second predetermined amount when the speed of the car has decreased to a second predetermined speed.

3. In combination, a stretch of railway track, 10 a fluid pressure operated car retarder, and means controlled by a car passing through said car retarder for controlling the pressure of the fluid supplied to said car retarder to control the braking force exerted on the car by the car retarder 15 in such manner that the braking force exerted on said car will decrease a first predetermined amount when the car speed decreases to a first predetermined speed and a second predetermined amount when the car speed decreases to a second 20 predetermined speed which is less than said first predetermined speed.

4. In combination, a stretch of railway track, 25 a fluid pressure operated car retarder, and means controlled by a car passing through said car retarder for controlling the pressure of the fluid supplied to said car retarder to control the braking force exerted on the car by the car retarder in such manner that the braking force exerted on 30 said car by said car retarder will decrease a predetermined amount when the car speed decreases to a selected one of a plurality of predetermined speeds and will decrease to zero when the car speed decreases to a second predetermined speed which is less than said first selected predetermined speed. 35

5. In combination, a stretch of railway track, 40 a braking bar extending parallel with one of the rails of said stretch and adapted to be at times moved toward the associated rail for engagement with the wheels of a passing car to retard the speed of the car, operating means for said braking bar, a series of relays adapted to be successively operated by the wheels of a car traversing said stretch for time intervals which depend on the speed of the car, a first series of timing relays each controlled by a different one of said first mentioned relays, a second series of timing relays each controlled by a different one of said 45 first mentioned relays and each being adapted to operate at the expiration of a different time interval from that at which the corresponding relay of the first series is adapted to operate, and means controlled by said timing relays for controlling said operating means. 50

6. In combination, a stretch of railway track, 55 a braking bar extending parallel with one of the rails of said stretch and adapted to be at times moved toward the associated rail for engagement with the wheels of a passing car to retard the speed of the car, a series of contacts, means controlled by a car traversing said stretch for successively operating said contacts for time intervals which depend upon the speed of the car, a first relay controlled by said contacts in such manner that said first relay will become operated if and only if one of said contacts remains operated for more than a predetermined time interval, a second relay controlled by said contacts in 70 such manner that said second relay will become operated if and only if one of said contacts remains operated for a time interval which is somewhat longer than that required to cause said first relay to operate, and means controlled in part by 75

- said two relays for controlling the braking action of said braking bar.
7. In combination, a stretch of railway track, a braking bar extending parallel with one of the rails of said stretch and adapted to be at times moved toward the associated rail for engagement with the wheels of a passing car to retard the speed of the car, a series of contacts, means controlled by a car traversing said stretch for successively operating said contacts for time intervals which depend upon the speed of the car, a first relay controlled by said contacts in such manner that said first relay will become energized if and only if one of said contacts remains operated for more than a predetermined time interval, a second relay controlled by said contacts in such manner that said second relay will become energized if and only if one of said contacts remains operated for a time interval which is somewhat longer than that required to cause said first relay to operate, pressure responsive means for operating said braking bar, manually controlled means effective when said first and second relays are both deenergized for supplying said pressure responsive means with fluid at different pressures to cause said braking bar to exert different braking forces, means effective when said first relay becomes deenergized for decreasing the pressure of the fluid supplied to said pressure responsive means to decrease the braking force exerted by said braking bars, and means effective when said second relay becomes energized for cutting off the supply of fluid pressure to said pressure responsive means.
8. In combination, a stretch of railway track, a fluid pressure operated car retarder for retarding the speed of a car traversing said stretch, two relays, manually controlled means effective when both of said relays are deenergized for supplying said car retarder with fluid at different pressures to cause said car retarder to exert different braking forces, means effective when a first one of said relays becomes energized for decreasing the pressure of the fluid supplied to said car retarder, means effective when the other relay becomes energized for cutting off the supply of fluid to said car retarder, and means controlled by the speed of a car traversing said stretch for selectively energizing said relays.
9. In combination, a stretch of railway track, a fluid pressure operated car retarder for retarding the speed of a car traversing said stretch, two relays, manually controlled means effective when both of said relays are deenergized for supplying said car retarder with fluid at different pressures to cause said car retarder to exert different braking forces, means effective when a first one of said relays becomes energized for decreasing the pressure of the fluid supplied to said car retarder, means effective when the other relay becomes energized for cutting off the supply of fluid to said car retarder, means for energizing said first relay when and only when the speed of a car which is traversing said stretch is below a predetermined speed, and means for energizing said other relay when and only when the speed of a car which is traversing said stretch is below a speed which is somewhat lower than said predetermined speed.
10. In combination, a stretch of railway track, a fluid pressure operated car retarder for retarding the speed of a car traversing said stretch, two relays, manually controlled means effective when both of said relays are deenergized for supplying said car retarder with fluid at different pressures to cause said car retarder to exert different braking forces, means effective when a first one of said relays becomes energized for decreasing the pressure of the fluid supplied to said car retarder, means effective when the other relay becomes energized for cutting off the supply of fluid to said car retarder, means for energizing said first relay when the speed of a car which is traversing said stretch decreases to a selected one of a plurality of predetermined speeds, and means for energizing said other relay when the speed of a car which is traversing said stretch decreases to a speed which is somewhat less than the selected speed at which said first relay releases.
11. In combination, a stretch of railway track, a braking bar located in the trackway adjacent one of the rails of said stretch and movable toward and away from such one rail into braking and non-braking positions, a series of short insulated control sections formed in one rail of said stretch, a series of track relays; a plurality of track circuits each including a different one of said control sections, the opposite rail, a different one of said track relays and a source of current; a first series of slow releasing timing relays one controlled by a back contact of each track relay, a second series of slow releasing timing relays one controlled by a back contact of each track relay and each having a longer release time than the release time of the corresponding relay of the first series, and means controlled by said timing relays for controlling said braking bar.
12. In combination, a stretch of railway track, a braking bar located in the trackway adjacent one of the rails of said stretch and movable toward and away from such one rail into braking and non-braking positions, a series of short insulated control sections formed in one rail of said stretch, a series of track relays; a plurality of track circuits each including a different one of said control sections, the opposite rail, a different one of said track relays and a source of current; a first series of slow releasing timing relays one controlled by a back contact of each track relay, a second series of slow releasing timing relays one controlled by a back contact of each track relay and each having a longer release time than the release time of the corresponding relay of the first series, and means controlled by said timing relays for controlling said braking bar.
13. In combination, a stretch of railway track, a braking bar located in the trackway adjacent one of the rails of said stretch and movable toward and away from such one rail into braking and non-braking positions, a series of short insulated control sections formed in one rail of said stretch, a series of track relays; a plurality of track circuits each including a different one of said control sections, the opposite rail, a different one of said track relays and a source of current; a first series of slow releasing timing relays one controlled by a back contact of each track relay, a second series of slow releasing timing relays one controlled by a back contact of each track relay and each having a longer release time than the release time of the corresponding relay of the first series, a first slow releasing control relay controlled by the timing relays of the first series, a second slow releasing control relay controlled by the timing relays of the second series, and means controlled by said control relays for controlling said braking bar.
14. In combination, a stretch of railway track, a braking bar located in the trackway adjacent one of the rails of said stretch and movable toward and away from such one rail into braking and non-braking positions, a series of short insulated control sections formed in one rail of said stretch, a series of track relays; a plurality of track circuits each including a different one of said control sections, the opposite rail, a different one of said track relays and a source of current; a first series of slow releasing timing relays one controlled by a back contact of each track relay, a second series of slow releasing timing relays one controlled by a back contact of each track relay and each having a longer release time than the release time of the corresponding relay of the first series, a first control relay provided with a plurality of pickup circuits each including a back contact of a different one of the timing relays of the first series, a second

control relay provided with a plurality of pick-up circuits each including a back contact of a different one of the timing relays of the second series, and means controlled by said control relays for controlling said braking bar.

14. In combination, a stretch of railway track, a braking bar located in the trackway adjacent one of the rails of said stretch and movable toward and away from such one rail into braking and non-braking positions, a series of short insulated control sections formed in one rail of said stretch, a series of track relays; a plurality of track circuits each including a different one of said control sections, the opposite rail, a different one of said track relays and a source of current; a first series of slow releasing timing relays one controlled by a back contact of each track relay, a second series of slow releasing timing relays one controlled by a back contact of each track relay and each having a longer release time than the release time of the corresponding relay of the first series, a first control relay provided with a plurality of pickup circuits each including a back contact of a different one of the timing relays of the first series, a second control relay provided with a plurality of pickup circuits each including a back contact of a different one of the timing relays of the second series, a fluid pressure operated device for operating said braking bar, means effective when said control relays are both deenergized for supplying said device with fluid at different pressures, means effective when said first control relay becomes energized for decreasing the pressure of the fluid which is supplied to said device a predetermined amount, and means effective when said second control relay becomes energized for cutting off the supply of pressure to said device.

15. In combination, a stretch of railway track, a fluid pressure operated car retarder for controlling the speed of a car traversing said stretch, a first series of contacts, means controlled by a car traversing said stretch for successively closing the contacts of said first series for time intervals which depend upon the speed of the car, a second series of contacts one for each contact of the first series, means for closing each contact of the second series if the corresponding contact of the first series remains closed for more than a predetermined time interval and for subsequently maintaining the contact closed until the corresponding contact of the first series opens, a speed control lever having an "off" position and a plurality of "on" positions, a quick to pick up, slow to release relay, a plurality of circuits for said quick to pick up, slow to release relay each including a different one of the contacts of said second series, a first and a second slow to pick up and slow to release relay, a plurality of circuits for said first slow to pick up and slow to release relay including a different one of the contacts of said second series and a contact of said lever which is closed in one of its "on" positions, a plurality of circuits for said second slow to pick up and slow to release relay including a different one of the contacts of said second series and a contact of said lever which is closed in another of its "on" positions, manually controlled means effective when all of said relays are deenergized for supplying said car retarder with fluid at different pressures to cause said car retarder to exert different braking forces, means effective when said quick to pick up, slow to release relay becomes energized for reducing the pressure of the fluid supplied to said car retarder a predetermined amount, and means effective when either of said slow to pick up and slow to release relays becomes energized for cutting off the supply of fluid pressure to said car retarder.

17. In combination, a stretch of railway track, a braking bar located in the trackway adjacent one of the rails of said stretch and movable toward and away from said one rail into braking and non-braking positions, a series of relatively short insulated control sections formed in one rail of said stretch, a series of track relays one for each control section but the last, each said relay of said series being provided with a main magnet for picking up the relay and an auxiliary magnet for assisting the release of the relay, a track relay associated with the last control section, a plurality of track circuits one for the main magnet of each relay of the series and each including the associated control section, the opposite rail of the stretch and a source of current; a circuit for the auxiliary magnet of each track relay of the series but the last including a front contact of the relay and a front contact of the relay next in advance, a circuit for the auxiliary magnet for the last relay of the series including a front contact of the relay and a front contact of the track relay associated with the last control section; a track circuit for the track relay associated with the last control section, the opposite rail of the stretch and a source of current; and means controlled by said series of track relays for controlling said braking bar.

18. In combination, a stretch of railway track, a fluid pressure operated car retarder for controlling the speed of a car traversing said stretch, a first series of contacts, means controlled by a car traversing said stretch for successively clos-

ing the contacts of said first series for time intervals which depend upon the speed of the car, a second series of contacts one for each contact of the first series, means for closing each contact of the second series if the corresponding contact of the first series remains closed for more than a predetermined time interval and for subsequently maintaining the contact closed until the corresponding contact of the first series opens, a speed control lever having an "off" position and a plurality of "on" positions, a quick to pick up, slow to release relay, a plurality of circuits for said quick to pick up, slow to release relay each including a different one of the contacts of said second series, a first and a second slow to pick up and slow to release relay, a plurality of circuits for said first slow to pick up and slow to release relay including a different one of the contacts of said second series and a contact of said lever which is closed in one of its "on" positions, a plurality of circuits for said second slow to pick up and slow to release relay including a different one of the contacts of said second series and a contact of said lever which is closed in another of its "on" positions, manually controlled means effective when all of said relays are deenergized for supplying said car retarder with fluid at different pressures to cause said car retarder to exert different braking forces, means effective when said quick to pick up, slow to release relay becomes energized for reducing the pressure of the fluid supplied to said car retarder a predetermined amount, and means effective when either of said slow to pick up and slow to release relays becomes energized for cutting off the supply of fluid pressure to said car retarder.

19. In combination, a stretch of railway track, a braking bar located in the trackway adjacent one of the rails of said stretch and movable toward and away from said one rail into braking and non-braking positions, a series of relatively short insulated control sections formed in one rail of said stretch, a series of track relays one for each track section but the last and each provided with two opposing magnets one of

which is stronger than the other, the parts being so proportioned that when the one magnet of a track relay becomes energized the relay will close its front contacts and open its back contacts and that if the other magnet becomes energized while one magnet is energized the front contacts of the relay will remain closed; a plurality of track circuits each including the one magnet of a different one of the track relays 10 of said series, a different one of said control sections, the opposite rail of the stretch, and a source of current; a circuit for the other magnet of each of the track relays of the series but the last including a front contact of the 15 relay and a front contact of the relay next in advance; a track relay associated with the last control section of the series, said relay being provided with a track circuit which includes the associated track section, the opposite rail of the 20 stretch, and a source of current; a circuit for the other magnet of the last track relay of the series including a front contact of the relay and a front contact of the track relay associated with the last track section, and means controlled by said series of track relays for controlling said braking bar.

19. In combination, a stretch of railway track, a fluid pressure operated car retarder for retarding the speed of a car traversing said 30 stretch, two relays, manually controlled means effective when both of said relays are deenergized for supplying said car retarder with fluid at different pressures to cause said car retarder to exert different braking forces, means effective 35 when a first one of said relays becomes energized for decreasing the pressure of the fluid supplied to said car retarder, means effective when the other relay becomes energized for cutting off the supply of fluid to said car retarder, 40 and means for selectively energizing said relays.

20. In combination, a stretch of railway track, a series of relatively short insulated control sections formed in one rail of said stretch, a 45 series of track relays one for each control section but the last, each said relay of said series being provided with a main magnet for picking up the relay and an auxiliary magnet for assisting the release of the relay, a track relay 50 associated with the last control section, a plurality of track circuits one for the main magnet of each relay of the series and each including the associated control section, the opposite rail of the stretch and a source of current; a circuit for the auxiliary magnet of each track 55 relay of the series but the last including a front contact of the relay and a front contact of the relay next in advance, a circuit for the auxiliary magnet for the last relay of the series including a front contact of the relay and a front contact of the track relay associated with the last control section; a track circuit for the track relay associated with the last control section including the last control section, the opposite 60 rail of the stretch and a source of current; and traffic governing means controlled by said series of track relays for controlling said braking bar.

21. In combination, a stretch of railway track,

a series of relatively short insulated control sections formed in one rail of said stretch, a series of track relays one for each track section but the last and each provided with two opposing magnets one of which is stronger than the other, 5 the parts being so proportioned that when the one magnet of a track relay becomes energized the relay will close its front contacts and open its back contacts and that if the other magnet becomes energized while one magnet is energized 10 the front contacts of the relay will remain closed; a plurality of track circuits each including the one magnet of a different one of the track relays of said series, a different one of said control sections, the opposite rail of the stretch, and a 15 source of current; a circuit for the other magnet of each of the track relays of the series but the last including a front contact of the relay and a front contact of the relay next in advance; a track relay associated with the last control section of the series, said relay being provided with a track circuit which includes the associated track section, the opposite rail of the stretch, and a source of current; a circuit for the other magnet of the last track relay of the series including a front contact of the relay and a front contact of the track relay associated with the last track section, and traffic governing means controlled by said series of track relays.

22. In combination, a stretch of railway track, 30 fluid pressure operated braking apparatus for retarding the speed of a car traversing said stretch, means for supplying said apparatus with fluid at a selected one of a plurality of predetermined pressures, and means for automatically 35 reducing the pressure of the fluid supplied to said apparatus a first predetermined amount if the speed of the car which is traversing said stretch decreases to a speed which is between a first and second predetermined speeds and for 40 further reducing said pressure or restoring it to its initial value if the car speed subsequently decreases below said second predetermined speed or increases above said first predetermined speed.

23. In combination, a stretch of railway track, 45 fluid pressure operated braking apparatus for retarding the speed of a car traversing said stretch, means for supplying said apparatus with fluid at a selected one of a plurality of predetermined pressures, and means for automatically 50 reducing the pressure of the fluid supplied to said apparatus a first predetermined amount if the speed of the car which is traversing said stretch decreases to a speed which is between a first and second predetermined speeds, for reducing said pressure a second predetermined 55 amount if the speed of the car decreases below a second predetermined speed, for again increasing said pressure the amount it was reduced when the speed of the car decreased below said 60 second predetermined speed if the speed of the car subsequently increases above said second predetermined speed, and for restoring said pressure to its initial value if the speed of the car subsequently increases above said first predetermined speed.

HERBERT L. BONE.
